BITE GAUGE

Joseph E. Kovats, Chicago, Ill.

Application April 18, 1938, Serial No. 202,635

3 Claims. (Cl. 33—148)

This invention relates to a novel and original bite gauge to determine the central axis of the hinge between the upper and lower jaw bones of man for dental or surgical purposes. An important and wide field for its use is found in dentistry in the making of dentures, when it is required to determine the normal position of the jaws in a natural bite of the patient, without lateral or frontal displacement.

The invention may also find wide use for surgical purposes.

It has long been known that the patient cannot definitely determine his natural bite, when a dentist is making a simple denture or a full denture. The object of the invention is to provide a bite gauge which, with the co-operation of the patient opening and closing his jaws at the direction of the dentist, will indicate by a suitable signal when said normal bite has occurred. With such normal bite the final denture may be made.

Other objects and advantages of the invention will more fully appear from the following specification:

This application is a continuation in part of my copending application, Serial No. 113,935, filed December 2, 1936.

In the drawing:

Fig. 1 is a perspective view of one embodiment of the invention, with some parts broken away to more clearly illustrate the internal construction;

Fig. 2 is a plan view of a cover plate referred to more particularly later.

Fig. 3 is a cross-section of the device in a plane indicated by the line 3—3 of Fig. 1.

My invention depends for its operation upon the known fact that when the jaws are closed to a bite, with frontal or lateral displacement, little or no enlargement or bulging of the jaw muscles occurs. But when the jaws swing together upon their normal central hinge axis and are brought together in their natural, intended normal bite position, a rigid expansion of all the muscles involved in mastication occurs.

Referring now to that embodiment of the invention illustrated in the drawing: 10, 10 indicate opposed pressure-gauges or pressure-reacting plungers which are designed for engagement with opposite sides of the face in the neighborhood of the hinge axis of the jaws. Said plungers are spring-controlled and are adapted for yielding engagement under pressure against the face, being each mounted for longitudinal movement in an opening 10^a in an arm 11, which carries it.

Any suitable spring mounting for the plunger 10 may be used.

12 indicates a cylindrical fitting having a base 12^a by means of which it is attached to the associated arm 11. The plunger 10 is mounted for longitudinal movement in said fitting and is normally retained against movement by means of a helical spring 13 surrounding it and fixed to it at one end, said spring being seated at its other end against the base 12^a of the fitting.

Obviously, by means of the arms 11, 11, the opposed ends of the plungers 10 may be engaged against opposite sides of the face and brought by the arms 11, 11 into yielding engagement therewith. By proper adjustment of the pressure the plungers may be made to lightly indent the skin and approach indirect engagement with the greater resistant jaw muscular structure therebelow. Then upon expansion of said muscular structure, the resistant action of the springs 12^b will be overcome and the plungers 10 will be snapped further apart in their mounting openings 10^a and the arms 11.

Since the movement of the plungers 10 is but a small fraction of a centimeter, their movement, whether to indirectly engage the jaw muscles or their further movement apart upon expansion of the jaw muscles, is too small for ready observation. I, therefore, prefer to employ an amplifying device for indicating such movement.

In the drawing, 13 indicates a lever needle pivotally mounted on a pin 13^a in a casing 14 in the plane of the arm 11 and plunger 10. Said needle has a short arm engaging said plunger and a much longer arm associated with a scale 15 remote from the plunger 10. A spring 13^b holds the shorter arm of the needle in engagement with the plunger. An intermediate point 15^a in the scale corresponds to the position of the plunger when the plunger has been brought to a position depressing the skin of the face and approaching indirect contact with the more resistant jaw muscles. Thereafter when a proper bite is given, the needle will snap to its limit of movement indicated on the scale at 15^b.

The arms 11 are pivotally connected at their ends remote from the plungers 10 to a plate 16. Said plate has an arcuate rib 17 and a horizontal rib 18 arising from its face and spaced apart at their ends to provide openings 19, 19 through 50 which the ends of the arms 11, 11 extend. Each arm is pivotally connected to the plate 16 by a pin 20 at a point short of its end. 21 indicates a block slidable upon the plate 16. 22 indicates a screw threaded through said block and through 55

the arcuate rib 17 beyond which it has a knurled head 23 fixed to it. The screw itself is locked against endwise movement by means of a pin 24 mounted in the rib 17 and engaging a groove in the screw. Obviously rotation of the screw 22 will cause the block 21 to travel in one direction or the other between the rib 18 and the rib 17. The block 21 is provided with lateral flanges 25, each provided with upwardly inclined slots 25^a. Each arm 11 is bifurcated at its end beyond its pivot pin 20 and embraces a flange 25 of the block 21 and is provided with pivotal relation therewith by means of a pin 26. The plate 16^a shown in Fig. 2 is adapted to be attached to the ribs 17 and 18, thus providing a closed casing in which the parts above described are held.

By the foregoing construction, it is obvious that micrometer-like adjustment of the arms 11, 11 towards or away from each other may be made by turning the screw 22 in one or the other direction.

The arms 11, 11 are preferably made long enough so that when the plungers 10 are brought to the desired position on the sides of the face, said arms will depend below the chin of the patient, so that the operator may steady his hold on the apparatus when using it by resting his hand against the chest of the patient.

The operation of the device is as follows: By proper adjustment of the screw 22, the plungers 10, 10 are applied to the sides of the face in the neighborhood of the central hinge axis of the jaws. The plungers are then brought lightly into engagement with the skin, the adjustment being continued until the skin is slightly indented and the ends of the plungers have come to indirect contact with the jaw muscles. This point may be predetermined and indicated on the scale 15 as heretofore pointed out. Thus in the case illustrated, the adjustment is continued until the needle of both arms comes to comparative rest at the point 15^a on the scale.

The patient is then required to open and close his jaws several times to make a proper bite. This, however, will have no effect on the plungers as long as there is front or lateral displacement of the jaws. When, however, a bite without such displacement is produced, the jaw muscles will immediately expand and force the plungers 10 farther apart, causing the needle 13 to snap

from its position at the point 15^a to point 15^b against the arm 11. This indicates to the operator that the bite is the normal bite of the patient.

The advantages of the invention will be manifest to those familiar with the art.

While in describing one embodiment of my invention I have referred to many details of construction and arrangement of parts and have illustrated but one form of indicating device, it will be understood that said details and arrangement may be modified in several ways, and that the invention is not limited thereto except as may be pointed out in the appended claims.

I claim as the invention:

1. A bite gauge comprising a base, spaced arms each pivotally connected at one end to said base and being free at the other end, means mounted on said base in operative engagement with said arms for providing micrometer adjustments of the space between the free ends of said arms, spring controlled opposed plungers carried at the free end of said arms and a visual indicating device for each arm adapted to indicate the movement of said plungers.

2. A bite gauge comprising a base, spaced arms each pivotally connected at one end to said base and being free at the other end, means mounted on said base in operative engagement with said arms for providing micrometer adjustments of the space between the free ends of said arms, spring controlled opposed plungers carried at the free ends of said arms and a visual indicating device for each arm adapted to indicate a predetermined initial and a final movement of its associated plunger.

3. A bite gauge comprising a base, spaced arms each pivotally connected at one end to said base and being free at the other end, means mounted on said base in operative engagement with said arms for providing micrometer adjustments of the space between the free ends of said arms, spring controlled opposed plungers carried at the free ends of said arms, an amplifying device for registering the movement of said plungers, and a visual indicating device associated with said amplifying device adapted to indicate a predetermined initial and a final movement of said plungers.

JOSEPH E. KOVATS. 50
